UNITED STATES PATENT OFFICE.

JOHN H. STEVENS AND NELSON CORY, OF SAN ANTONIO, TEXAS.

SUPPORT FOR OXY-ACETYLENE TORCHES.

Application filed June 19, 1924. Serial No. 721,099.

To all whom it may concern:

Be it known that we, JOHN H. STEVENS and NELSON CORY, citizens of the United States, residing at San Antonio, in the county of Bexar and State of Texas, have invented certain new and useful Improvements in Supports for Oxy-Acetylene Torches, of which the following is a specification.

Our invention is a frame for supporting an oxy-acetylene torch and has for its object the provision of a strong durable frame of simple construction whereby an oxy-acetylene torch may be supported adjacent the work and guided so that the cutting flame from the torch will be caused to follow a path corresponding to the contour of the material to be cut. Another object of the invention is to provide a construction whereby the guiding member may be changed at will according to the work to be done, and a further object is to provide simple and compact means whereby the work will be firmly secured in the frame. These objects and other objects which will hereinafter incidentally appear are attained in such an apparatus as is illustrated in the accompanying drawings, and the invention resides in certain novel features which will be particularly pointed out in the appended claims.

In the drawings:

Figure 1 is a side elevation of our improved device showing a railroad track rail in section and supported therein;

Fig. 2 is a plan view of the device, and

Fig. 3 is a detail perspective view of the guide plate.

In carrying out our invention, we employ a base plate 1 having reinforcing ribs 2 formed on its under side and constructed with a central slot 3 in which a cam lever 4 is mounted. The base plate is also constructed at one side with an overhanging flange or lip 5 which is disposed in divergent relation to the surface of the base plate, as shown most clearly in Fig. 1, whereby one base flange 6 of a track rail may be engaged under the said lip and held by the same and the base plate. The head 7 of the cam lever 4 is adapted to bear against the base flange of the track rail opposite the lip 5 and when it is turned home force the rail firmly against the bight presented by the said lip and the base plate so that the rail will be securely held while it is being acted upon by the torch. The reinforcing ribs 2 are provided

with a plurality of openings 8 therethrough and the cam lever is likewise provided with a plurality of openings 9 so that the fulcrum bolt 10 may be engaged through the proper openings to set the cam lever for any particular work.

The ribs 2 merge into a standard 11 which extends outwardly and upwardly from the base plate and the lip 5 and constitutes the main support for the carrier 12 in which the torch is secured. By reference to Fig. 2, it will be noted that the carrier 12 is disposed so that the sleeve or barrel 13 in which the end of the torch will be held is adjacent but beyond the side edge of the base plate and, consequently, the flame from the torch may be directed upon and over the entire extent of the work without playing upon the base plate as the torch is manipulated. The carrier consists of a bar at one end of which the sleeve 13 is formed and which is provided with longitudinal slots 14 in which are fitted bolts 15 carrying rollers 16 which play in the slots 17 and 18 of the guide plate 19. The guide plate is secured rigidly upon the standard 11 parallel with the same and in spaced relation thereto by shouldered bolts 20 having their threaded extremities inserted through the standard and through the upper and lower ends of the guide plate, respectively, as clearly shown, so that, when nuts fitted on the extremities of the said bolts are turned home, the guide plate and the standard will be firmly secured together and held in the spaced relation. The bolts 15 which are inserted through the slots 14 of the carrier 12 are engaged through a handle or lever 21 disposed between the guide plate and the standard 11 and close to the guide plate so that the carrier and the handle will be held adjacent the guide plate and will be thereby prevented from having lateral movement. The forward bolt 15 passes through and plays in the slot 18 in the guide plate which extends rearwardly or outwardly and slightly upwardly with respect to the work while the outer bolt 15 plays through the cam slot 17 which is of a general arcuate form concentric with the front end of the slot 18 and has offset portions 22 adjacent its ends.

It is thought to be evident from the foregoing description, taken in connection with the accompanying drawings, that, as the handle or lever 21 is swung upwardly or downwardly, the inner or front bolt 15 will

serve as a pivot about which the vertical movement may occur. At the same time the handle may be given an eccentric or irregular movement which will cause the sleeve 13 to advance or recede relative to the work as well as swing vertically relative thereto, and this eccentric movement will be accelerated and emphasized by the engagement of a roller 16 with the offsets 22 of the guide slots 14. The longitudinal slots 14 in the carrier permit the same to be adjusted endwise with respect to the handle so that the head 13 may be set at a greater or less distance beyond the inner edge of the guide plate according to the dimensions of the rail or other part which is to be operated upon. The guide plate may have the slot 17 of any desired form so that the movement of the torch will follow the outline of the work, and it is the intention to supply guide plates in various forms so that they may be used interchangeably as circumstances may demand.

Having thus described the invention, we claim:

1. A device for the purpose set forth comprising a base plate, means for clamping work thereto, a guide plate secured rigidly upon the base plate, a carrier disposed at one side of the guide plate and parallel therewith, a handle disposed at the opposite side of the guide plate and parallel therewith, and means for rigidly connecting the handle and the carrier, said means being operatively engaged with and extending through the guide plate whereby to impart to the carrier movement along a line corresponding to the contour of the work.

2. A device for the purpose set forth comprising a base plate, means for clamping work to the base plate, a standard on the base plate at one side thereof, a guide plate secured rigidly to the standard in spaced relation thereto and adjacent an edge of the

base plate, said guide plate being provided approximately midway its height with a slot extending in a direction toward and from the work and further provided with an arcuate cam slot extending in the general direction of its height, said arcuate slot being described about a center located in the first-mentioned slot, a carrier arranged adjacent one side of the guide plate, a handle arranged adjacent the opposite side of the guide plate, and connections between the carrier and the handle playing in the slots in the guide plate whereby the carrier may be caused to move over a path corresponding to the contour of the work.

3. A device for the purpose set forth comprising a base plate, means for clamping work to the base plate, a standard on the base plate at one side of the work, a guide plate secured rigidly to the standard in spaced relation thereto, said guide plate being provided substantially midway its height with a slot extending in a general horizontal direction toward and from the work and being further provided with an arcuate cam slot extending in the general direction of its height, said arcuate slot being described about a center located in the first-mentioned slot, a carrier arranged adjacent one side of the guide plate and provided with aligned longitudinal slots, a handle arranged adjacent the opposite side of the guide plate, and connecting bolts secured in the handle member and engaged in the longitudinal slots of the carrier and extending through and playing in the respective slots in the guide plate whereby the carrier may be caused to move over a path corresponding to the contour of the work.

In testimony whereof we affix our signatures.

NELSON CORY. [L. S.]
JOHN H. STEVENS. [L. S.]
